UNITED STATES PATENT OFFICE.

JOSEPH V. HULL, OF NEW YORK, N. Y., ASSIGNOR, BY MESNE ASSIGNMENTS, TO ANCHOR CAP & CLOSURE CORPORATION, OF NEW YORK, N. Y., A CORPORATION OF NEW YORK.

RECEPTACLE-CLOSURE.

1,134,068.

Specification of Letters Patent. Patented Mar. 30, 1915.

Application filed July 25, 1912. Serial No. 711,426.

To all whom it may concern:

Be it known that I, JOSEPH V. HULL, a citizen of the United States, and a resident of the city of New York, county of Kings, 5 borough of Brooklyn, State of New York, have invented certain new and useful Improvements in Receptacle-Closures, (Case A,) of which the following is a specification.

10 My invention relates to caps for sealing jars or receptacles in which the outer surface of the upper part of the receptacle gradually increases its diameter. By my invention I am enabled to provide such jars 15 with a cap adapted to be locked in place on the jar or receptacle which cap is very much more economical than those heretofore in use on jars of this character. By my invention I also provide a tongue whereby the 20 cap may be readily removed from the receptacle without the use of any implement.

Figure 1 shows my cap in place on a glass tumbler; Fig. 2 shows a cross-section of the same; and Fig. 3 is an enlarged illustration 25 of a portion of my cap before the jar is sealed.

In the drawings in which like letters refer to like parts A represents a glass tumbler or receptacle in which, as shown, the receptacle 30 is of a tapering form—that is its outer surface gradually increases in diameter until the top of the receptacle is of greater diameter than the base, and the tumbler is not provided at its top with any shoulder except 35 such as is formed by the gradual increase in diameter of the receptacle.

B is a cap which is made to conform to the form of the top of the receptacle, and is corrugated so as to form grooves or beads 40 G which extend entirely around the cap near its edge. The cap B is provided with a downwardly extending flange C, and depending from the downwardly extending flange C is a skirt D, a trifle larger in diameter, 45 connected with the flange C by a beading E.

F is a tongue extending from the lower edge of the beading surface E and not connected with the skirt D except through the 50 medium of the beading E.

H is a gasket which may be of paper or other suitable material.

In sealing a receptacle with my improved cap the cap, which is preferably made just a trifle smaller than the top of the receptacle, as shown in Fig. 3, is placed thereon, then the receptacle is forced upward inside of a chuck which tends to exert pressure upon the skirt D in a horizontal direction thereby causing the beading E to exert 60 a pressure upon the flange C at its lower point inward toward the receptacle which causes the metal of the flange C to roll inward until it engages with the receptacle making a locking seal around a portion of 65 the receptacle which is of less diameter than the top of the receptacle. The corrugations on top of the cap tend to give a resiliency to the metal to assist in holding the cap in place, while at the same time the under side 70 of the corrugations of the cap engage with the washer to compress same against the top of the receptacle. When it is desired to remove the cap the same may be done by an outward pull on the tongue F which 75 tends to distort the cap and enable easy access to the receptacle.

What I claim is:

A cap for sealing tapered glass containers and the like comprising a body equipped with 80 a downwardly extending flange tapered inwardly, a skirt extending outwardly and having a greater diameter than the flange, an annular beading between the flange and the skirt, a gasket adapted to form a top 85 seal with the container, the said annular beading being adapted to lock the cap to the container upon the reduction in diameter of the skirt, and a tongue separate from the skirt and connected directly with the 90 beading, and adapted to loosen the latter to remove the cap.

In testimony whereof, I have signed my name to this specification, in the presence of two subscribing witnesses,

JOSEPH V. HULL.
